(57) CLAIM

The ornamental design of tongs with joined shank, as shown
and described.

DESCRIPTION

FIG. 1 is a perspective view showing our new tongs with
joined shank;

FIG. 2 is a front elevational view thereof;

FIG. 3 is a rear elevational view thereof;

FIG. 4 is a right side elevational view thereof, the left side
elevational view being a mirror image of that which is
shown; and,

FIG. 5 is a top plan view thereof, the bottom plan view
thereof being a mirror image of that which is shown.
